UNITED STATES PATENT OFFICE.

CHARLES F. PIKE, OF PROVIDENCE, RHODE ISLAND.

IMPROVEMENT IN RAILROAD-CAR HEATERS.

Specification forming part of Letters Patent No. 124,973, dated March 26, 1872.

SPECIFICATION.

I, CHARLES F. PIKE, of the city and county of Providence, in the State of Rhode Island, have invented certain new and useful Improvements in "Apparatus for Heating Cars;" and it consists in passing the exhaust steam from the locomotive-engine through suitable pipes, first through the feed-water in the tender and then successively to heaters under the cars, from whence the heat is distributed to pipes and registers in the cars, all of which will be more fully described in the following specification, reference being had to the accompanying drawing forming a part thereof.

To enable others skilled in the art to make and use my invention, I will now proceed to more definitely describe the same.

In the drawing, Figure 1 is a plan of a train connected, showing my apparatus in position. Fig. 2 is a side view of the same. Figs. 3, 4, 5, 6, and 7 are enlarged views of the locomotive, tender, and car, with my apparatus in position.

In the drawing, A represents a locomotive; B, the tender; and B', a car. The exhaust-pipes C C' of the locomotive are connected to the smoke-arch, and are arranged under the foot-boards on each side of the locomotive. At the rear end of the locomotive they turn down a short distance and then pass into the tender B, running along the bottom thereof, and heat the feed-water in the tanks. The exhaust steam then passes through suitable pipes a a' to the heaters E, arranged under each car, and finally, at the end of the train, is blown into the air. In summer the exhaust steam may be blown out through a pipe, b, by closing the cock c. The heaters are inclosed in a non-conducting case, d, and contain a number of small tubes, e, through which the exhaust steam passes, heating the oil or other non-congealable fluid in the heater E, or the tubes may be filled with oil and the steam pass around them. Each car is provided with a double floor, f f', and between these floors are arranged the pipes F F'. From the heaters a branch pipe, i, leads the heat into the pipes F F', which are connected by a cross-piece, g. The heated liquid, passing up one side and returning, passes through the pipes h into the bottom of the heater E, to be there again heated, and so on automatically, keeping up a constant circulation. To gain access to the heater a trap-door may be arranged in the

floor of the car, or a door in the side of the case d. The heat developed by the pipes F F' passes through registers G, shown in dotted lines, which are arranged between the seats of the cars and ventilators H in the sides of the cars, with an opening at the bottom to create a constant current of air, and thereby keep the cars well ventilated; it being well known that the cold air by its gravity descends, and the heated air will follow after, until the cars are well warmed and an equal temperature obtained throughout. In the bottom of the heaters are arranged small cocks for letting out the condensed water. The pipes are all connected by flexible, universal, or slip joints of the usual kind.

The great advantages of my invention are, first, perfect safety, there being but one fire on a train—viz., in the furnace of the locomotive—and of course no accidents can occur from upsetting of stoves, and thereby the liability of being burnt to death is avoided. An equal temperature can be maintained in the whole car, and not, as now with stoves, the passengers near the stove obtaining all the benefit therefrom and those in the center none; second, saving of fuel in the stoves.

When it is desired to heat the cars before starting the virgin steam may be run through the pipes and heaters until the train is in motion, when the exhaust steam may be used, which heretofore was consumed for creating a draught in the locomotive itself to assist in the combustion of the fuel.

Having thus described my invention, what I claim, and desire to secure by Letters Patent, is—

1. The arrangement of exhaust-pipes C, pipes a F h i, heaters E, registers G, and ventilators H, all substantially as shown, and for the purpose set forth.

2. The method herein described for warming and ventilating railroad cars, consisting in passing steam (waste or virgin) through pipes in contact with a system of coils or pipes inclosed in air-flues, boxes, or chambers so that the steam heats the liquid in said coils or pipes, and the liquid by automatic circulation heats the air, so as to warm and ventilate the cars, substantially as set forth.

CHARLES F. PIKE.
